BALLPOINT PEN

Marcel Louis Michel Antoine Bich, Neuilly-sur-Seine, France, assignor to Societe Bic, Societe Anonyme de Droit Francais, Clichy, France

Filed Oct. 18, 1968, Ser. No. 14,058

Claims priority, application France July 30, 1968

Term of patent 14 years

Int. Cl. D19—06

U.S. Cl. D74—17

FIG1

FIG2

FIG3

FIG5

FIG4

FIG6

FIG. 1 is a side elevational view of a ballpoint pen showing my new design;

FIG. 2 is a front elevational view thereof as it appears with the writing point in retracted position;

FIG. 3 is a rear elevational view thereof;

FIG. 4 is a top plan view of the pen shown in FIG. 2 and rotated 180 degrees;

FIG. 5 is a cross-sectional view on line 5—5 of FIG. 3; and

FIG. 6 is a cross-sectional view on line 6—6 of FIG. 3.

I claim:

The ornamental design for a ballpoint pen, as shown and described.
